BEACH CLEANING MACHINE

Victor H. Chatten, Torrance, Calif., assignor to
 Sanitized Beaches, Inc., Torrance, Calif., a corporation of California

Application November 12, 1948, Serial No. 59,539

12 Claims. (Cl. 55—17)

1

This invention relates to mobile sifter or screening apparatus employing a conveyor with vibrating bucket elements for sorting, screening and separating one class of material from another. While this invention has a broad range of useful embodiments, I have chosen to illustrate it in connection with a mobile device for cleaning beach sand by removing all of the foreign material, debris and trash. The machine is adapted to travel along the surface of a bathing beach and to clean the sand at any desired depth within its operative range.

The problem of cleaning bathing beaches adequately often becomes acute. Resort communities recognize that the beaches must be kept clean if tourists are to be attracted, but the mounting labor costs for cleaning the beaches manually by using rakes and the like becomes a very heavy burden. I have found that my invention as embodied in a beach cleaning machine is capable of alleviating this burden and of reducing the cost per square yard of cleaning bathing beaches while at the same time producing superior results.

An object of my invention is to provide a mobile unit capable of moving at a relatively rapid rate along a bathing beach for cleaning a swath at any desired depth within the range of operation of the device.

Another object is to provide a mobile bucket-like conveyor having means for vibrating the buckets as they travel to separate trash, debris and the like from beach sand, so that the sand may be immediately returned to the beach without excessive handling thereof, while the debris and trash may be deposited in a mobile or attached container for disposal at locations away from the beach.

Another object is to provide a mobile beach cleaner having right and left plow devices at its forward end for scooping the sand into a central mound to provide side clearance for the lower drive sprockets of the bucket conveyor.

Another object is to provide a novel form of vibratory bucket construction well adapted for severe service conditions encountered in screening abrasive beach sand.

Another object is to provide a device of this type in which the screened sand is returned to the cut directly behind the buckets which scoop up the sand, the cut being held open by means of parallel vertical side plates until the screened sand is returned into it.

Another object is to provide means for orienting normally free swinging buckets immediately prior to their digging operation in order that such

2

digging may be performed with maximum efficiency.

Other objects and advantages will appear hereinafter.

5 In the drawings:

Figure 1 is a side elevation showing a preferred embodiment of my invention.

10 Figure 2 is a top plan view of the beach cleaning machine itself, the tractor and rubbish wagon being omitted.

Figure 3 is a side elevation partly broken away showing details of the forward portion of the beach cleaner.

15 Figure 4 is a sectional elevation of the forward end of the device taken substantially on the lines 4—4 as shown in Figure 2.

Figure 5 is a front sectional elevation taken substantially on the lines 5—5 as shown in Figure 4.

20 Figure 6 is a sectional view partly broken away taken substantially on the lines 6—6 as shown in Figure 2.

Figure 7 is a sectional detail showing a preferred bucket construction taken substantially on the lines 7—7 as shown in Figure 6.

25 Figure 8 is a partial sectional detail taken substantially on the lines 8—8 as shown in Figure 7.

Figure 9 is a diagrammatic side elevation partly broken away, showing the crawler-type supporting wheels in an inoperative position for highway travel.

30 Figure 10 is a perspective view of the knife edge cutter assembly which is positioned at the extreme forward end of the device.

35 Referring to the drawings, the frame 10 may be carried on a truss wheel assembly 11 provided with an endless crawler-type track 12 adapted to roll on a beach. The track is sufficiently wide to prevent the machine from sinking into the sand. The frame 10 includes an inclined section 13 upon which operates an endless bucket conveyor generally designated 14. The forward end of the inclined portion 13 is joined integrally with a horizontally extending forward projection 15 to which a tow bar 16 is pivotally connected by means of the pin 17. A hitch connection 18 is provided for attachment to a towing tractor 19.

40 A prime mover 20 which may take the form of an internal combustion engine is mounted on a rearward extension 21 of the frame 10 and is adapted to drive a countershaft 22 by means of a multiple V-belt assembly 23. Suitable transmission connections are provided whereby the countershaft 22 may rotate the line shaft 24.

Additional transmission connections are provided whereby the line shaft 24 may rotate the upper sprocket shaft 25 carried on the upper end of the inclined section 13. A clutch 26 actuated by a lever 27 is provided so that the shaft 25 may be driven or held at rest as desired while the prime mover 20 is operating. Supplementary transmission connections including the belts 28 and 29 are provided for operating the drive pulley 30 on the lower shaft 31 of the picking belt assembly generally designated 32. This assembly includes the lower pulley 30 at one end of the belt 33 and an upper pulley (not shown) at the other end of the belt 33. From this description it will be understood that the general mode of operation is that sand and trash are scooped up in the screen buckets 34 on the endless conveyor 14. The sand is screened as the buckets travel in carrying position upwardly along the upper flight of the conveyor, and the trash is deposited on the upper flight of the picking belt 33 and transported to the trash outlet 35 from whence it falls by gravity into the rubbish wagon 36. This rubbish wagon may be of any suitable style or size and is conveniently towed behind the frame 10. A platform 37 is provided on the frame 10 in a location so that an operator standing on the platform may inspect the trash, rubbish, debris, etc. moving upwardly along the picking belt 33 and may thus sort out coins, jewelry or other valuables before they are deposited with the debris in the rubbish wagon 36.

Considering the construction of the endless conveyor in more detail, a pair of endless chains 38 pass over pairs of drive sprockets 39 and 40 at opposite ends of the conveyor assembly 14. The lower sprockets 39 are carried on a shaft 41 mounted in spaced bearing assemblies 42. The upper sprockets 40 are mounted on a drive shaft 43 carried in spaced bearing assemblies 44. The bearing assemblies 44 may be provided with adjusting elements 45 for regulating the slack in the chains 38.

As shown in the drawings the individual buckets 34 are pivotally mounted on the links of the chains 38. Parallel pivot shafts 46 extend between links of the parallel chains 38 and are held in place by retaining rings 47. Each pivot shaft 46 extends through bosses 48 formed on parallel side members 49 of the bucket assemblies 34. A spacer sleeve 50 encircles the pivot shaft 46 between the end members 49. Tie bars 51, 52, 53 and 54 also extend between the end members 49. The forward or digging portion 55 of each bucket 34 is curved as shown in Figure 7. The curved bottom portion of the bucket extending from the digging portion 55 to the sleeve 50 is formed as a wire mesh screen 56. This screen is attached to the digging lip 55 at 57 at one end and rests against the sleeve 50 and tie bar 54 at the other end. These curved screens 56 forming the bottom of the buckets 34 are mounted for easy removability so that they may be replaced when worn out. Each of the buckets 34 may be provided with vertical spacer plates 58. It will be understood that the space between the forward edge 59 of the digging lip and the spacer sleeve 50 is open and that each bucket is filled through this open side. The parts of the buckets may be assembled by any convenient means, and I have found welding to be a very satisfactory method of joining the component parts thereof.

Parallel channels 60 and 61 forming a part of 75

the frame 13 support the conveyor assembly and carry idler rollers 62 for the upper flight of the chains 38. These rollers 62 may be mounted for rotation on pins 63 carried by the parallel channels 60 and 61. Mounted on the inner channels 60 and 61 is a pair of ratchet bars 64 secured in position by means of a suitable attachment fitting 65. A strip of rubber or rubber-like material 66 is preferably interposed between the supporting channel and the ratchet bar 64. Each of these bars 64 is formed with a plurality of upwardly directed tooth elements 67. Each of the end members 49 on the buckets 34 is provided with a follower 68 having a face 69 adapted to ride on the inclined faces 70 of the ratchet teeth 67. Accordingly, ascending movement of the upper flight of the chains 38 causes the buckets to be vibrated in an oscillatory fashion about the axis of the pivot shafts 46. It is recognized that the ratchet bars 64 could be formed in any convenient manner to vibrate the buckets 34 on the ascending flight of the conveyor chains. Such vibration could be parallel to the axis of the pivot shafts 46 or in an arc about that axis or both.

I have found that the particular ratchet system shown in the drawings gives excellent results, particularly in connection with the shape of the buckets as illustrated, since the oscillatory or vibratory motion of the bucket is such as to shift the contents of the bucket to avoid clogging of the screen openings. The ratchet teeth are preferably spaced so that the individual buckets do not all drop at the same instant, but on the contrary drop in sequence to avoid build up of shock loads. The ratchet bars 71 may be provided for the lower flight of the conveyor chains 38. These lower ratchet bars are not essential along the lower portion of the lower flight of the chains. When the ascending buckets pass over the upper drive sprocket 40 the buckets invert and swing freely for a short interval until the follower surface 69 strikes the lower ratchet bars 71. As shown in Figure 3 the lower ratchet bar 71 may be continued for a short distance to insure that the trash drops out of the buckets. Baffles 72 are provided on the frame to insure that the trash drops onto the moving belt 33. The buckets in the lower flight of the conveyor move downwardly but do not swing freely on their pivot shafts 46, since the follower surfaces 69 ride along the smooth portion 73 of the lower ratchet bars 71. As shown in Figure 4 when the individual buckets 34 approach the lower end of the lower flight of the conveyor, the follower surfaces 68 leave the smooth guide 73 and fall against the projecting end of a leaf spring assembly 74. As the forward edge 59 of the digging lip of each bucket swings into digging position the arm 75 on each of the followers 68 is engaged by the boss 48 on the next bucket to the rear, with the result that the bucket is caused to fill with sand through its forward opening. As the individual buckets 34 move around the lower drive sprocket 40 they are held in position by the cooperative action of the follower 68 resting against the bosses 48 on the next bucket to the rear. The heel portion 76 of each bucket just clears the stationary curved member 77 on the frame 10 and the turning movement of each bucket is thereby continued. The buckets pass upwardly without any substantial vibration until the follower surfaces 69 engage the beginning end 78 of the upper ratchet bars 64. The oscillatory vibration of the buckets effected by the coaction between the follower

surfaces 69 and ratchet teeth 67 is then effective to cause the sand in the buckets to sift through the screen bottoms and fall downwardly against the inclined baffles 79, 80, 81 and 82. The sand falling from the buckets in the upper flight "rains" downwardly through the spaces between the buckets in the lower flight and is returned to the cut from whence it came. This is accomplished by providing the upper inclined baffle 80 and the lower floor 81. As shown in Figure 4 the floor 81 is joined at its forward end by a guide 82 having a strike bar 83 at its lower end.

The forward projection 15 at the front end of the frame 10 supports a bracket 84 having downwardly and forwardly projecting supports 85. The knife blade 86 is carried at the extreme ends of the supports, and this blade extends slightly below the cutting depth of the buckets 34. The purpose of the blade 86 is to cut any grasses or vegetation which may be growing in the sand and to warn of the existence of any hidden obstacles which might interfere with the digging action of the buckets.

Since the conveyor chains operate at the ends of the buckets, it is necessary to provide clearance for the sprockets 39 so that they may operate satisfactorily with the conveyor chains 38 and may not become unduly packed with sand. In order to provide clearance for these sprockets 39 and for the chains 38 at their lowest operative point a pair of right and left plowshares 87 and 88 are mounted at the forward end of the frame just behind the horizontal cutting blade 86. These plows each form a furrow by throwing the sand into a central mound between them. This increases the effective working depth of the buckets in their digging action and allows the machine to clean a wider strip of beach than would otherwise be possible for a given length of conveyor bucket, as well as for providing clearance for the sprockets and chains. Parallel vertical side plates 89 and 90 extend downwardly into the furrows formed by the plowshares 87 and 88 respectively and serve to hold the sand outside the plates 90 from spilling into the furrows. These side plates extend rearwardly beyond the digging location for the buckets and serve to hold the cut open until the screened sand is returned to it.

Thus, as shown in Figure 4, the side plates extend rearwardly of the lowermost buckets and rearwardly of the strike bar 83. Sand which falls from the bucket screens passes downwardly over the inclined floor 81 and enters the cut between the side plates immediately in advance of the strike bar 83.

The leaf springs 74 are carried on transverse angle irons 91 which are in turn supported on a carrier bracket 92. The bracket 92 is fixed to the frame by attachment fittings 93. The spring 74 is sufficiently resilient to act as an effective cushion for the otherwise free swinging buckets, as well as to align the cutting edge 59 thereof in proper position just prior to making a cut in the sand.

Means are provided for controlling the depth of cut of the buckets, and as shown in the drawings this means includes a hydraulic cylinder assembly 94 connected to actuate the quadrant 95 secured on the tow bar 16. When the cylinder assembly 94 is lengthened the tow bar is moved to the dotted line position shown in Figure 4. This has the effect of raising the entire forward end of the frame 10 so that the blade 86, plows 87 and 88, buckets 34 and side plates

89 and 90 are raised clear of the level of the beach. The cutting depth of the buckets may be regulated by varying the angular position of the tow bar 16 with respect to the frame 10. The forward end of the tow bar is pivotally connected to the tractor by the hitch 18, and since the hitch is placed at a fixed height variation in angular position of the tow bar serves to vary the height of the forward end of the beach cleaning machine.

For highway transportation to and from beaches it is highly desirable to replace the endless tracks 12 with a more suitable form of wheel. I prefer to accomplish this changeover by installing relatively large diameter road wheels 96 on the axles 97 as shown in Figure 9. The truss wheel assembly 11 is held in inoperative position by means of platforms 98 held in place by tension rods 99. These rods are secured to the frame 10.

In operation the road wheels 96 are removed and the device is wheeled off the platforms 98 so that the endless tracks 12 rest on the ground surface. The tow bar 16 is inclined sufficiently to hold the forward end of the device clear of the ground surface while it is being maneuvered into position on the beach. The rubbish wagon is then attached and the tractor moves forwardly. The tow bar 16 is adjusted by regulating the position of the hydraulic cylinder assembly 94 so that the buckets cut to the desired depth. The engine 20 on the frame 10 drives the conveyor chains 38 and also drives the belt 33 on which the rubbish, trash and debris are deposited. The tractor pulls the entire device along the beach so that the buckets on the lower flight of the conveyor chains move downwardly and the buckets on the upper flight move upwardly. Vibration of the buckets sifts the sand through the screen bottoms and returns it to the cut which is maintained open by means of the vertical side plates 89 and 90. The trash, debris, etc. falls from the buckets as the chains pass around the upper sprockets 40.

While I have shown hinged guard sections 100 enclosing the conveyor assembly, these guards may, of course, be omitted or other forms of guards may be employed.

I have found under conditions of actual use that it may be desirable to provide bumper strips or wear strips of very hard metal for reducing the wear between various parts which meet in metal-to-metal contact. Thus, it may be desirable to provide hard metal wear strips on the buckets 34 and on the curved shield 77. I have found that very good service life is achieved when the ratchet bars 64 are formed of Hadfield manganese steel, and the bucket ends including the followers 63 may be made of the same material.

While I have chosen to illustrate my invention in connection with a machine for cleaning beaches, it will be understood that the inventive features thereof may be embodied in machines for picking stones, removing clods, and generally separating coarse materials from fine materials along the path of travel of the device.

Having fully described my invention, it is to be understood that I do not wish to be limited to the details herein set forth, but my invention is of the full scope of the appended claims.

I claim:

1. In a device of the class described, the combination of mobile frame, an inclined moving conveyor assembly on the frame, said assembly including a plurality of self-loading buckets, each

bucket having a screen portion adapted to allow relatively fine material to sift therethrough while retaining relatively coarse material in the bucket; and cooperating means on said frame and said buckets for vibrating the buckets as a consequence of the conveyor movement, said means cooperating with a follower including ratchet means to vibrate the buckets individually and out of synchronism.

2. In a beach cleaning machine, the combination of a mobile frame; an inclined power driven conveyor assembly on the frame, said assembly including a plurality of self-loading buckets each having a screen portion adapted to allow beach sand to sift therethrough while retaining trash and debris; and ratchet bars on the frame cooperating with followers on the buckets for vibrating the buckets relative to the frame, the ratchet bars having teeth spaced with relation to the followers so that the buckets vibrate out of synchronism.

3. In a beach cleaning machine, the combination of a mobile frame; inclined power driven conveyor chains on the frame, a plurality of self-loading buckets each pivotally mounted on said chains, each bucket having a curved screen portion adapted to allow beach sand to sift therethrough while retaining trash and debris; ratchet bars carried on the frame cooperating with followers provided on the buckets for oscillating the buckets about their pivotal supports; and rubber-like strips interposed between the ratchet bars and the frame for cushioning the shock occasioned by cooperative action of the ratchet bars and followers.

4. In a sorting and screening device of the class described, the combination of a mobile frame; an inclined power driven conveyor assembly carried on the frame, said assembly including sprocket members at the lower end thereof, and a plurality of self-loading buckets each provided with a screen to allow relatively fine material to sift therethrough while retaining relatively coarse material in the bucket; transversely spaced means at the forward end of the frame and in longitudinal alignment with said sprocket members for forming parallel furrows into which said sprockets are adapted to extend; and parallel side plates near the forward end of the frame adjacent said sprockets, said side plate extending into the furrows to maintain the furrows open to provide clearance for the sprocket members.

5. In a device of the class described, the combination of a mobile frame; an inclined power driven conveyor assembly carried on the frame, said assembly including sprocket members at the lower end thereof, and a plurality of self-loading buckets; transversely spaced means at the forward end of the frame and in longitudinal alignment with said sprocket members for forming parallel furrows with a mound therebetween in advance of the buckets and into which said sprockets are adapted to extend; and parallel side plates near the forward end of the frame adjacent said sprockets, said side plates extending into the furrows to maintain the furrows open to provide clearance for the sprocket members.

6. In a beach cleaning machine, the combination of a mobile frame; an inclined power driven conveyor assembly on the frame, said assembly including endless chains having a plurality of self-loading buckets pivotally mounted thereon; transversely spaced means on the forward end of the frame adapted to form parallel furrows and a central mound therebetween; a pair of side

plates on the frame extending into the furrows on either side of the buckets in loading position; each of the buckets having a digging lip for engaging the mound and a screen portion adapted to allow beach sand to sift therethrough while retaining trash and debris; stationary means on the frame for vibrating the buckets as a consequence of movement of the conveyor chains; and baffle means on the frame for returning the sand falling from the vibrating buckets to a location between said side plates.

5 7. In a beach cleaning machine, the combination of a mobile frame; an inclined power driven conveyor assembly on the frame, said assembly including an endless chain having a plurality of self-loading buckets pivotally mounted thereon and adapted to scoop up sand from a beach, each of the buckets having a screen portion adapted to allow beach sand to sift therethrough while retaining trash and debris; stationary means on the frame for vibrating the buckets as a consequence of movement of the conveyor chains, a power driven endless belt operatively mounted on the frame and adapted to receive trash and debris from said buckets, and baffle means on the frame for returning the screened sand to the beach adjacent the position from whence it was taken.

15 8. In a beach cleaning machine, the combination of a mobile frame; an inclined power driven conveyor assembly on said frame, said assembly including endless chains having a plurality of self-loading buckets pivotally mounted thereon, transversely spaced means on the forward end of the frame adapted to form parallel furrows and a central mound therebetween in advance of the buckets, a pair of side plates on the frame extending into the furrows on either side of the buckets in loading position; each of the buckets having a screen portion adapted to allow beach sand to sift therethrough while retaining trash and debris; stationary means on the frame for vibrating the buckets on both upper and lower flights of the conveyor chains; and resilient means near the lower end of the conveyor assembly for orienting the buckets on the lower flight of the conveyor chains into proper positions for self loading.

25 9. In a beach cleaning machine, the combination of a mobile frame; an inclined power driven conveyor assembly on the frame, said assembly including a plurality of self-loading buckets each having a screen portion adapted to allow beach sand to sift therethrough while retaining trash and debris; and ratchet bars on the frame cooperating with followers on the buckets for vibrating the buckets relative to the frame, each of said followers cooperating with a boss on the next following bucket to prevent oscillatory motion of the buckets while the buckets are carried around the lower end of said conveyor assembly.

30 10. In a device of the class described, the combination of a frame, a power driven conveyor assembly on said frame, said conveyor including a plurality of self-loading buckets, each bucket having a screen portion adapted to allow relatively fine material to sift therethrough while retaining relatively coarse material in the bucket, and means for vibrating the buckets while said buckets are in the carrying position, said means including ratchet bars on the frame cooperating with followers on the buckets, the ratchet bars having teeth spaced with relation to the followers so that the buckets vibrate out of synchronism.

11. In a beach cleaning machine, the combina-

tion of a mobile frame; inclined power driven conveyor chains on the frame, a plurality of self-loading buckets each operably mounted on said chains, each bucket having a screen portion adapted to allow beach sand to shift therethrough while retaining trash and debris; ratchet bars carried on the frame cooperating with followers provided on the buckets for vibrating the buckets relative to the frame; and rubber-like strips interposed between the ratchet bars and the frame for cushioning the shock occasioned by cooperative action of the ratchet bars and followers.

12. In a device of the class described, the combination of a mobile frame; an inclined power driven conveyor assembly carried on the frame, said assembly including a pair of spaced sprocket members at the lower end thereof, and a plurality of self-loading buckets; a pair of transversely spaced plow members at the forward end of the frame and in longitudinal alignment with said spaced sprocket members for forming parallel furrows with a mound therebetween in advance

of the buckets and into which said spaced sprocket members are adapted to extend; and parallel side plates near the forward end of the frame adjacent said spaced sprocket members, said side plates extending into the furrows to maintain the furrows open to provide clearance for the said spaced sprocket members.
